United States Patent Office

Des. 209,082
Patented Oct. 31, 1967

209,082

LOCK COVER OR THE LIKE

Bailey C. Williams, 1200 Marlboro Road,
Raleigh, N.C. 27610

Filed Aug. 12, 1966, Ser. No. 3,462

Term of patent 14 years

(Cl. D50—7)

The figure is a perspective view of a lock cover or the like, the unexposed portion thereof being identical to that shown.

What is claimed is:

The ornamental design for a lock cover or the like, as shown and described.

References Cited

UNITED STATES PATENTS

D. 48,087 11/1915 Smith ----- D50—7

OTHER REFERENCES

Presto Lock Hardware Cat. © 1963, p. 23, bottom right #372/1172 lock item.

WALLACE R. BURKE, Primary Examiner.

WILLIAM WERTMAN, Assistant Examiner.